APPLIANCE FOR DELIVERING PLASTIC
SUBSTANCES UNDER HIGH PRESSUREFriedrich Banz, Erlenbach, near Zurich,
SwitzerlandApplication September 7, 1949, Serial No. 114,336
In Switzerland June 16, 1949

3 Claims. (Cl. 18—30)

1

The present invention relates to an appliance for delivering plastic substances under high pressure.

Known appliances for delivering plastic substances have, for taking the plastic substance, two pressure chambers which are alternately filled and alternately emptied through a common mouthpiece. While the substance is being pressed out of one pressure chamber and being filled into the other, the connection between the two chambers through the common ejection mouthpiece is to be broken, the member which effects this connection or this interruption having to keep tight against the high pressing pressure and being therefore complicated to construct and control.

The appliance according to the invention has two pistons which are arranged concentrically to each other and are axially displaceable independent of each other in a pressure chamber connected to the ejection mouthpiece for the substance and to a storage container for the substance, an annular member coupled to the inner piston being arranged in this chamber axially displaceable along the wall of the chamber.

One example of execution according to the invention is illustrated in the accompanying drawing.

According to this drawing, in a pressure chamber 1 with ejection mouthpiece 2 for the plastic substance, two pistons 3 and 4 are displaceable arranged, which are concentric to each other and movable independent of each other. The inner piston 3 has a piston plate 6 displaceable in the pressure cylinder 5, whilst the outer hollow piston 4 is connected to the piston plate 8 displaceable in the pressure cylinder 7.

In the pressure chamber 1 an annular member 9 is arranged displaceable along the wall of the pressure chamber; the bore in this member is less than the diameter of the inner piston 3, and the member is held between the end of the piston 3 and four ribs 10 extending radially out from the piston. This annular member 9 is thus coupled to the piston 3 and moves with it, whereby it is movable between the end of the piston and the ribs 10 serving as displacing means.

On the pressure chamber 1 a funnel-shaped storage container 11 is fitted for holding the plastic mass to be pressed; the container 11 is in connection with the pressure chamber 1 through an opening 12, this opening being controlled by the piston 4.

Pipes 13 to 16 allow of a pressure medium, for instance oil, being admitted and/or led away for

moving the pistons. As can be seen from the following description of the method of working of the appliance, this admission and removal of the pressure medium is controlled in a certain rhythm by means not shown in the drawing.

Starting with the parts in the position illustrated, the piston 3 moves towards the ejection opening 2 and thereby carries the annular member 9 along with it, so that the substances in front of the piston and member 9 is compressed and ejected. At the same time the space behind the annular member 9 and round the piston 3 fills with plastic substance from the storage container 11. The following piston 4 compresses this substance, pressing out any air present in it, up to the pressure prevailing in front of the piston 3. In addition, piston 4 closes the opening 12 when passing along, and the piston 3 commences its return stroke. The annular member 9 then comes to lie against the ribs 10, and the substance delivered by the piston 4 flows through the bore of the ring past the ribs 10 into the end of the pressure chamber 1 where the ejection mouthpiece 2 is located. When the pistons 3 and 4 have simultaneously arrived respectively at the rear end and at the front end of their strokes, their directions of motion are reversed. The annular member 9 comes to lie against the tapered front end of the piston 3, and the plastic substance in front of the ring 9 and the piston is pressed out through the ejection mouthpiece, after which the described cycle starts again.

What I claim is:

1. In a device for delivering plastic substances under pressure, in combination, an inner piston and an outer piston in coaxial arrangement to each other, a common pressure chamber in which said pistons are axially movable, an ejection mouthpiece at one end of said pressure chamber, a storage container connected to said chamber at a point rearwardly of the position of furthest rearward movement of said inner piston, spaced abutments on the forward end of the inner piston, said end being of reduced diameter adjacent said abutments, and an annular member having a bore in which is received the said end of reduced diameter and having an external diameter corresponding to the diameter of said chamber, said annular member being slidable along the inner wall of said chamber and movable between said spaced abutments and the main portion of the said inner piston, said end of said inner piston being movable into closing relation with the bore in the annular member on the forward stroke

2. In a device for delivering plastic substances under pressure in combination, an inner piston and an outer piston in coaxial arrangement to each other, a common pressure chamber in which said pistons are axially movable, an ejection mouthpiece at one end of said pressure chamber, a storage container connected to said chamber at a point rearwardly of the position of furthest rearward movement of said inner piston, the inner piston having a tapered end, ribs on said tapered end, an annular member slidable along the inner wall of said chamber and movable over the tapered portion of said inner piston between said ribs and the main portion of the piston and having an external diameter corresponding to the diameter of said chamber, the bore in said annular member being of less diameter than the outer diameter of said inner piston, and a communication port between said storage container and the pressure chamber at a point rearwardly of the position of furthest rearward movement of said inner piston and controlled by the outer piston, the tapered end of said inner piston being movable into closing relation with the bore in the annular member on the forward stroke thereof.

3. In a device for delivering plastic substances under pressure in combination, an inner piston and an outer piston in coaxial arrangement to each other, a common pressure chamber in which said pistons are axially movable, an ejection mouthpiece at one end of said pressure chamber, a storage container connected to said chamber, the inner piston having a tapered end, ribs on said tapered end, an annular member

slidable along the inner wall of said chamber and movable over the tapered portion of said inner piston between said ribs and the main portion of the piston and having an external diameter corresponding to the diameter of said chamber, the bore in said annular member being of less diameter than the outer diameter of said inner piston, and a communication port between said storage container and the pressure chamber at a point rearwardly of the position of furthest rearward movement of said inner piston and controlled by the outer piston, the tapered end of said inner piston being movable into closing relation with the bore in the annular member on the forward stroke thereof.
